INVENTOR.

UNITED STATES PATENT OFFICE.

FRANCIS L. HORSPOOL, OF SALT LAKE CITY, UTAH.

EMERGENCY LOCKING-BOLT FOR SAFE OR VAULT DOORS AND THE LIKE.

1,138,218.

Specification of Letters Patent.

Patented May 4, 1915.

Application filed August 9, 1913, Serial No. 783,981. Renewed September 26, 1914. Serial No. 863,772.

To all whom it may concern:

Be it known that I, FRANCIS LEROY HORSPOOL, a citizen of the United States, residing at Salt Lake City, in the county of 5 Salt Lake and State of Utah, have invented a new and useful Emergency Locking-Bolt for Safe or Vault Doors and the like, of which the following is a specification.

My invention relates to improvements in 10 emergency locking bolts, more especially to a bolt where a spring is used to throw the bolt into its locking position when the combination lock which is on the door be broken off.

One object of my invention, is to provide 15 an emergency locking bolt that will work by automatic action when the combination lock has been driven in or broken off.

Another object of my invention, is to provide 20 an emergency locking bolt that cannot be jarred loose and lock the safe by the closing of the door.

Another object of my invention, is to provide 25 an emergency locking bolt that can be held firmly into place and work automatically when the lock has been broken into.

Another object of my invention is to provide 30 an emergency locking bolt that is cheap in construction and can be applied to any style of safe or vault door by unskilled labor.

Another object of my invention is to provide 35 an emergency locking bolt that can be held firmly unlocked by a wire attached to the cap of the tumblers of the combination.

With these and other objects in view my invention consists of the following novel construction and arrangements of parts, to 40 be hereinafter described and claimed, reference being had to the annexed drawings forming part of this specification and to the figures of reference marked thereon.

Figure 1 is a fragmentary vertical sectional view showing the invention applied 45 to the door of the safe, ready for use. Fig. 2 is a transverse sectional view looking toward the door from the inside of the safe. Fig. 3 is an enlarged detail of the invention

50 showing the spring compressed and the device ready for use. Fig. 4 is an enlarged detail of the invention showing the spring expanded and the bolt in the locked position. Fig. 5 is a detail of the plunger. Fig. 6 is a detail of the locking bolt. Fig. 7 is a detail of the cylinder or casing. Fig. 8 is a

detail of one style of locking bolt which is to be used in place of the devices shown in Figs. 5 and 6, when the bolt is placed on the bottom of the door. Fig. 9 is a detail view 60 of the lower end 6 of the casing 1.

Similar letters and numerals refer to like parts throughout the several views of the drawings.

A designates a fragmentary section of a 65 safe provided with a door B carrying the combination lock C.

1 is the tubular casing.

2 is the spring.

3 is the plunger.

4 is the bolt.

The tubular casing 1, is swelled at the upper end 5 forming a taper. The lower end 6 being flanged inwardly at 7, forming the hole 8 through which passes the stem 3 of the plunger. A hole 9 is drilled in the tubular casing 1 near the upper end 5 into which is placed a lead ball 10. A sticker 11 is placed over the hole 9 to prevent the ball 10 from dropping out. The locking bolt 4 80 is grooved at 14. In the lower end of the plunger stem 3 is a hole 12, the upper end having a head 13.

Having thus described the parts of my invention I will endeavor to illustrate the operation and assembling of same.

I start by first drilling a hole 15 into the door frame 16 of the door B. This hole is tapering so it will fit the tapered end 5 of the tubular casing 1. Now I drill a corresponding hole 17 into the door casing 18 which is for receiving the upper end of the locking bolt 4. Now I place into the hole 15 the tubular casing 1 and into the tubular casing 1, I place the spring 2, the plunger 95 3, and the locking bolt 4. Now I take the wire 19 securing one end into the hole 12 located in the end of the plunger 3, I now secure the other end firmly to a screw located in the back of the combination casing 20. Before securing the wire 19 to the screw I press down on the locking bolt and compress the spring then secure the wire, thus holding the bolt unlocked as shown in Fig. 3.

In the event that the combination mechanism is tampered with in any way by unauthorized persons, such as burglars who undertake to enter the safe by breaking through the dial of the combination lock 110 by driving in the spindle which pushes off the casing 20, thus releasing the tension on

the wire 19 which allows the spring 2, to expand and raise the plunger which pushes the bolt 4 into the hole 17 in the door casing 18, thus locking the door so it cannot be opened, as shown in Fig. 4. By the use of the wire 19 which is attached as described it is impossible for the bolt to be jarred loose, or thrown into a locking position by the closing of the door or any other known 10 means of jarring, such as falling.

When the bolt is in a locked position the ball 10 drops down into the groove 14, in the locking bolt 4 which will prevent the said bolt 4 from being pulled down in case that 15 the combination was blown out so that the burglar could reach in and secure a hold on the wire 19. He would be able to pull down the plunger, but the locking bolt 4 would still be retained in the locking position by the ball 10, as shown in Fig. 4. A groove 23 is cut into the side of the locking bolt 4 for the purpose of allowing the ball 10 to travel in when the bolt is thrown into a locked position. As the ball 10 is a little 25 larger than the clearance 24, it will be impossible for it to drop out of the hole 9 when the bolt is in a locked position. The ball is also prevented from being thrown out of the hole 9 by a sticker 11 which is 30 placed over the hole.

After the bolt 4 has been thrown into a locked position and I wish to open the door, I drill a hole 25 through the casing A and down through the filling until the drill 35 reaches the bolt 4, now I remove the drill and place in a pin and push the bolt 4 back into the casing 1, then the door will open as usual. The location of the bolt is taken by

measurement by the party who places the bolt onto the safe. 40

Having thus described my invention, what I claim as new and desire to secure by Letters Patent, is:

1. A device of the character described comprising a tubular casing, the upper end 45 thereof being tapered, said casing provided with a hole located near said tapered end, a ball within said hole, a bolt within said casing provided with a groove for receiving said ball when said bolt is in locked position, a plunger within said casing for operating said bolt, said casing having a hole in its lower end for receiving the stem on said plunge. 50

2. A device of the character described 55 comprising a tubular casing, the upper end thereof being tapered, said casing provided with a hole located near said tapered end, a sticker covering said hole, a ball within said hole, a bolt within said casing provided with 60 a groove for receiving said ball when said bolt is in locked position, a plunger within said casing for operating said bolt, a spring within said casing for operating said plunger, said casing having a hole in its lower 65 end for receiving the stem on said plunger, a wire secured to said stem and attached to the locking mechanism on the door, a hole in said door for receiving the tapered end of said tubular casing, substantially as and for the purpose set forth. 70

FRANCIS L. HORSPOOL.
